(57) **ABSTRACT**

An antenna array has two columns of dipoles that are configured to radiate distinct signals. The top and bottom row of dipoles have a coupler that splits the power of each column such that each of the two dipoles at top and bottom radiate in both signals at a given power split ratio. The coupler provides for phase compensation so that the two radiated signals are phase aligned across the top and bottom row. Having the power shared at the top and bottom rows shifts the phase center away from the edge of the ground plane of the antenna's reflector. The coupler is configured so that its coupling efficiency is greatest at the lowest frequency and least at its highest frequency. This improves the performance of the antenna array in the low frequencies while preserving antenna diversity between the two radiated signals.

FIG. 1

FIG. 2

FIG. 3

FREQUENCY-DEPENDENT COUPLER FOR ANTENNA ARRAY POWER SHARING

CROSS-REFERENCE TO RELATED APPLICATIONS

This application is a National Stage Application of International Application No. PCT/US24/14079 filed on Feb. 1, 2024, which claims the benefit of U.S. Provisional Application No. 63/482,602, filed on Feb. 1, 2023, all of which are incorporated by reference in their entirety herein.

BACKGROUND OF THE INVENTION

Multiport and multiband antennas have seen a steady increase in demand and complexity. The current demand from the industry is for multiband antennas that operate in the low band (LB) (617-860 MHz), mid band (MB) (1695-2690 MHz), C-Band and CBRS (Citizens Broadband Radio Service) (3.4-4.2 GHz). For each of these bands, antennas are required to operate with multiple signals. In the case of the low band, a common design requirement is for the antenna to have four dedicated ports, whereby the antenna may be configured with two independent columns of LB radiators, with each LB radiator configured to transmit and receive two independent signals, each at a different polarization (e.g., ± 45 degrees). Further complicating this is the demand that the multiband antenna be as narrow as possible to minimize wind loading.

FIG. 1 illustrates a four-port LB array 100 in a multiband antenna. LB array 100 has a reflector 105 on which are disposed two columns (two linear arrays) of LB radiators 110. Each column of LB radiators is fed two RF (Radio Frequency) signals, one per polarization. In the illustrated example, the left column of LB dipoles 110 is fed two RF signals, from ports 115a and 115b; and the right column of LB dipoles 110 is fed two RF signals, from ports 120a and 120b. Each column of LB radiators 110 has a phase center 132 or 135. In a typical antenna design, the space between the two columns of LB dipoles 110 may be reserved for subarrays of MB and/or C-Band dipoles (not shown) that may be disposed on reflector 105. Also not shown in FIG. 1 is a phase shifter or Remote Electrical Tilt (RET) mechanism that provides differential phasing to the LB dipoles 110 in each column to provide for tilting of the radiated beam in the vertical plane. The RET mechanism is omitted herein for simplifying the diagram as it is not pertinent to the description of antenna array 100.

As mentioned earlier, there is demand to reduce the width of reflector 105 to make the antenna as narrow as possible to mitigate wind loading. In response, a distance 160 from the outer edge of reflector 105 to phase center 135 may be narrow to where it affects the gain pattern of the LB dipoles 110.

Accordingly, what is needed is a multiport LB antenna array that provides for improved performance as well as a narrow reflector.

SUMMARY OF THE INVENTION

An aspect of the present disclosure involves an antenna array. The antenna array comprises a reflector plate; a first column (e.g., a first linear array) of dipoles disposed on the reflector plate; a second column (e.g., a second linear array) of dipoles disposed on the reflector plate, wherein the first column of dipoles and the second column of dipoles are arranged to form a top row of dipoles and a bottom row of

dipoles, where in the dipoles are configured to radiate in a frequency band; a top coupler coupled to a top pair of dipoles in the top row of dipoles; and a bottom coupler coupled to a bottom pair of dipoles in the bottom row of dipoles, wherein a first component of the top coupler and a first component of the bottom coupler are configured to receive a first signal and a second signal, to provide a phase compensation for the first signal and the second signal, and to couple the first signal and the second signal into a first output signal and a second output signal, wherein the first output signal is a mix of the first signal and the second signal at a first power ratio, and the second output signal is a mix of the first signal and the second signal at a second power ratio, wherein a second component of the top coupler and a second component of the bottom coupler are configured to receive a third signal and a fourth signal, to provide a phase compensation for the third signal and the fourth signal, and to couple the third signal and the fourth signal into a third output signal and a fourth output signal, wherein the third output signal is a mix of the third signal and the fourth signal at a third power ratio, and the fourth output signal is a mix of the third signal and the fourth signal at a fourth power ratio. The top coupler and the bottom coupler are configured to couple the aforementioned receive signals at a first efficiency corresponding to a low frequency of the frequency band and at a second efficiency corresponding to a high frequency of the frequency band. It should be noted that the terms "top" and "bottom" are used for ease of discussion and are not intended to reflect a relative vertical position. One skilled in the art would recognize that the term "top" and "bottom" could be easily be replaced with "first" and "second," respectively, of "left" and "right."

BRIEF DESCRIPTION OF DRAWINGS

FIG. 1 illustrates a conventional multiport LB antenna array.

FIG. 2 illustrates an exemplary multiport LB antenna array according to the disclosure.

FIG. 3 illustrates an exemplary arrangement of two exemplary couplers as deployed in the upper and lower rows of LB dipoles according to the disclosure.

FIG. 4 illustrates an exemplary dual coupler according to the disclosure.

DETAILED DESCRIPTION OF THE INVENTION

FIG. 2 illustrates an exemplary multiport LB antenna array 200 according to the disclosure. Antenna array 200 has a reflector 105 and two columns (e.g., two linear arrays) of LB dipoles 110, each of which is configured to radiate two independent signals, each at a different orthogonal polarization (e.g., ± 45 degrees). Accordingly, four ports provide signals to the exemplary LB antenna array 200. Reflector 105 and dipoles 110 may be substantially similar to those described above with respect to antenna array 100.

Not shown in FIG. 2 is a phase shifter or Remote Electrical Tilt (RET) mechanism that provides differential phasing to the LB dipoles 110 in each column to provide for tilting of the radiated beam in the vertical plane. The RET mechanism is omitted herein for simplifying the diagram as it is not pertinent to the description of exemplary antenna array 200. It will be understood how a RET mechanism would be integrated into the illustrated antenna array 200.

Antenna array 200 has four ports: ports 115a and 115b that feed RF signals to the left column of LB dipoles 110,

one per polarization, respectively via signal cables or traces **125a** and **125b**; and ports **120a** and **120b** that feed RF signals to the right column of LB dipoles **110**, one per polarization, respectively via signal cables or traces **130a** and **130b**. Signal cables or traces (for the sake of brevity, the term cable is used hereon) **125a**, **125b**, **130a**, and **130b** may have two conductors, one for its corresponding RF signal and one for its ground.

As illustrated, the middle three rows of LB dipoles **110** of each column couple directly to their respective ports (again, neglecting for the sake of brevity any intervening RET mechanism). It will be understood that more or less than three middle rows of LB dipoles is within the scope of the present disclosure. However, the uppermost LB dipoles **110** of both columns are coupled to the ports via dual couplers **240a** and **240b** such that, for the polarization corresponding to ports **115a** and **120a** (e.g., +45 degrees), their respective cables **125a** and **130a** couple to dual coupler **240a**, and for the polarization corresponding to ports **115b** and **120b** (e.g., -45 degrees), their respective cables **125b** and **130b** couple to dual coupler **240b**. Dual coupler **240a** has two outputs. Dual coupler **240a** is more broadly referred to as a first component of the top and bottom coupler in the Summary of the Invention section above. One couples to the first polarization (+45) radiators of uppermost LB dipole **110** of the left column and the other couples to the first polarization radiators of uppermost LB dipole **110** of the right column. Dual coupler **240b**, like dual coupler **240a**, has two outputs. Dual coupler **240b** is more broadly referred to as a second component of the top and bottom coupler in the Summary of the Invention section above. One couples to the second polarization (-45) radiators of uppermost LB dipole **110** of the left column and the other couples to the second polarization radiators of uppermost LB dipole **110** of the right column. The two bottom LB dipoles **110** are coupled similarly using a second set of dual couplers **240a** and **240b**.

Further illustrated in FIG. 2 are phase centers **232** and **235**. As illustrated, phase center **232** runs down the center of the middle three LB dipoles **110** of the left radiator column, and phase center **232** shifts toward the center of reflector **105** at the top and bottom LB dipoles **110**, due to the use of power sharing between the top and bottom two LB dipoles **110** due to the dual couplers **240a/b**, as described further below.

FIG. 3 illustrates an exemplary arrangement of exemplary dual couplers **240a** and **240b** as deployed in the upper and lower rows of LB dipoles **110** according to the disclosure.

Dual coupler **240a** is coupled to input cables **125a** and **130a** that respectively carry corresponding signals to/from ports **115a** and **120a**. In the Summary of the Invention section above, these signals are referred to as first and second signals. The signal from cable **125a** is fed to power divider **305**, which also provides for phase compensation (described below). The outputs of power divider **305** are fed to two coupler segments **315** and **320**. The signal from cable **130a** is fed to power divider **310**, which also provides for phase compensation. The outputs of power divider **310** are fed to the two coupler segments **315** and **320**. Coupler segment **315** has an output **325** that provides the +45 polarized signal to left column LB dipole **110**. In the Summary of the Invention section above, this signal is referred to as the first output signal. The signal at output **325** is a phase-aligned sum of signals from ports **115a** and **120a** with a power ratio determined by power dividers **305** and **310**. Similarly, coupler segment **320** has an output **330** that provides the +45 polarized signal to right column LB dipole **110**. In the Summary of the Invention section above, this signal is referred to as the second output signal. The signal at output **330** is a phase-aligned sum of signals from ports **115b** and **120b** with a power ratio that is the inverse of the power ratio provided to coupler segment **315**.

signal is referred to as the second output signal. The signal at output **330** is a phase-aligned sum of signals from ports **115a** and **120a** with a power ratio that is the inverse of the power ratio provided to coupler segment **315**.

Dual coupler **240b** has as input cables **125b** and **130b** that respectively carry corresponding signals to/from ports **115b** and **120b**. Dual coupler **240b** is more broadly referred to as a second component of the top and bottom coupler in the Summary of the Invention section above, and the signals to/from ports **115b** and **120b** are referred to as third and fourth signals. The signal from cable **125b** is fed to power divider **305**, which also provides for phase compensation (described below). The outputs of power divider **305** are fed to two coupler segments **315** and **320**. The signal from cable **130b** is fed to power divider **310**, which also provides for phase compensation. The outputs of power divider **310** are fed to the two coupler segments **315** and **320**. Coupler segment **315** has an output **325** that provides the -45 polarized signal to left column LB dipole **110**. In the Summary of the Invention section above, this signal is referred to as the third output signal. The signal at output **325** is a phase-aligned sum of signals from ports **115b** and **120b** with a power ratio determined by power dividers **305** and **310**. Similarly, coupler segment **320** has an output **330** that provides the -45 polarized signal to right column LB dipole **110**. In the Summary of the Invention section above, this signal is referred to as the fourth output signal. The signal at output **330** is a phase-aligned sum of signals from ports **115b** and **120b** with a power ratio that is the inverse of the power ratio provided to coupler segment **315**.

FIG. 4A illustrates an exemplary -15 dB dual coupler **240a/b** according to the disclosure. Each of dual coupler **240a** and dual coupler **240b** has four ports (i.e., two input and two output): first input port **405** that couples to a first signal input (e.g., **125a/b**); a first output port **410** that couples to one of the polarization elements of one LB dipole **110** (e.g., left column); a second input port **415** that couples to a second signal (e.g., **130a/b**); and a second output port **420** that couples to the same polarization element but of the other LB dipole **110** (e.g., right column). For purposes of illustration, first input port **405** may correspond to input port **115a/b**; first output port **410** may correspond to the left LB dipole **110**; second input port **415** may correspond to input port **120a/b**; and second output port **420** may correspond to the right LB dipole **110**. It will be understood that this first/second/left/right designation is for the purpose of illustration and that different designations are possible and within the scope of the disclosure.

Coupled to first input port **405** is a left pre-split trace **425**, which may have a meander pattern to impart a phase shift to maintain phase alignment between the first and second signals. Left pre-split trace **425** ends at a left power divider **430**, which splits left pre-split trace **425** into a left primary split trace **440** and a left secondary split trace **435**. Both left primary split trace **440** and left secondary split trace **435** may have further meander patterns for providing phase compensation in conjunction with the meander pattern of left pre-split trace **425**.

Left power divider **430** may be designed to split the power of the signal on left pre-split trace **425** into a desired power ratio between the signals respectively present on left primary split trace **440** and left secondary split trace **435**. This may be done by designing the respective widths of left primary split trace **440** and left secondary split trace **435** to tailor the power division. For example, a power split ratio of 70/30

may be achieved by setting the width of left primary split trace **440** to an appropriately greater than the width of left secondary split trace **435**.

Left primary split trace **440** becomes part of left coupler segment **447** (boundary illustrated by dotted line) and forms an output of left coupler segment **447** that couples to first output port **410**. Left secondary split trace **435** becomes part of right coupler segment **452** (boundary illustrated by dotted line) and terminates at a load **480** at the end of right coupler segment **452**.

Coupled to second input port **415** is a right pre-split trace **455**, which may have a meander pattern to impart a phase shift to maintain phase alignment between the first and second signals. Right pre-split trace **455** ends at a right power divider **460**, which splits right pre-split trace **455** into a right primary split trace **470** and a right secondary split trace **465**. Both right primary split trace **470** and right secondary split trace **465** may have further meander patterns for providing phase compensation, in conjunction with the meander pattern of right pre-split trace **455**.

Right power divider **460** may be designed to split the power of the signal on right pre-split trace **455** into a desired power ratio between the signals respectively present on right primary split trace **470** and right secondary split trace **465**. This may be done by designing the respective widths of right primary split trace **470** and right secondary split trace **465** to tailor the power division. For example, a power split ratio of 70/30 may be achieved by setting the width of right primary split trace **470** appropriately greater than the width of right secondary split trace **465**.

Accordingly, the signal at first output port **410** is a 70/30 sum of the signal at first input port **405** and second input port **415**, respectively; and the signal at second output port **420** is a 70/30 sum of the signal at second input port **415** and first input port **405**, respectively.

Right primary split trace **470** becomes part of right coupler segment **452** (boundary illustrated by dotted line) and forms an output of left coupler segment **452** that couples to second output port **420**. Right secondary split trace **465** becomes part of left coupler segment **447** and terminates at a load **480** at the end of left coupler segment **447**.

In addition to controlling the power split ratio (e.g. 70/30) by the relative widths of left power divider **430** and right power divider **460**, the coupling power imparted at left coupler segment **447** and right coupler segment **452** may be controlled through the width of the gap (not shown) between left primary split trace **440** and right secondary split trace **465** within left coupler segment **447**, and through the width of the gap (also not shown) between right primary split trace **470** and left secondary split trace **435** within right coupler segment **452**.

Another feature of left coupler segment **447** and right coupler segment **452** is a lateral translation **475** that extends the length of the traces respectively within left coupler segment **447** and right coupler segment **452**. The length of lateral translation **475** may determine the phase taper of dual coupler **240a/b** such that the efficiency of the coupling may be higher at the low frequency end of the Low Band than at the high frequency end.

Exemplary dual coupler **240a/b** illustrated in FIG. 4A may provide -15 dB coupling at 600 MHz and -22 dB coupling at 860 MHz. The coupling may be controlled through the relative thicknesses of first left primary split trace **440** and left secondary split trace **435**, and by the conjugate relative thicknesses of right primary split trace **470** and right secondary split trace **465**. Designing dual coupler **240a/b** so that it is a -17 dB coupler at 600 MHz

may be done either by making left and right primary split traces **440/470** thinner than for the -15 dB coupler, making left and right secondary split traces **435/465** thicker, increasing the gap (not shown) between the traces within coupler segments **447/452**, or some combination of the above. **435** This provides advantages. For example, a higher coupling at the low end (600 MHZ) increases the efficiency of the power sharing between the left and right LB dipoles **110**, effectively shifting phase center **232** to the right and phase center **235** to the left. This increases the distance **260** between phase center **232** and the left edge of the ground plane of reflector **105**, improving the gain profile generated by the left column of LB dipoles **110**; and it increases the phase distance **260** between phase center **235** and the right edge of the ground plane of reflector **105**, improving the gain profile generated by the right column of LB dipoles **110**.

Accordingly, having efficient coupling at the low end of the low band (e.g., 600 MHZ) shifts the phase center away from the edge of the ground plane of reflector **105**, which solves a problem disproportionately suffered at the low end of the low band. At the high end of the low band (e.g., 860 MHz), the distance **260** from phase center to the edge of the ground plane is not a problem. However, having less efficient coupling (e.g., -22 dB) at the high end of the low band (e.g., 860 MHz) helps preserve diversity of LB array **200** by maintaining isolation between the signal fed to input port **115a** and the signal fed to input port **120a** (and similarly to **115b** and **120b**). Otherwise, if the coupling efficiency were maintained constant at -15 dB, the two signals would mix between left and right columns of LB dipoles **110** such that antenna diversity would be undermined. Exemplary antenna array **200** may have improved performance by having dual couplers **240a/b** and the top and bottom rows of LB dipoles **110**, whereby the improved beam pattern at the top and bottom rows, due to shifting phase centers **232** and **235** toward the center of reflector **105**, improves the overall beam pattern of both the left and right columns of LB dipoles while maintaining isolation between the left and right columns to preserve diversity.

The invention claimed is:

1. An antenna array, comprising:
a reflector plate;
a first column of dipoles disposed on the reflector plate;
a second column of dipoles disposed on the reflector plate,
wherein the first column of dipoles and the second column of dipoles are arranged to form a top row of dipoles and a bottom row of dipoles, wherein the dipoles are configured to radiate in a frequency band;
a top coupler coupled to a top pair of dipoles in the top row of dipoles; and
a bottom coupler coupled to a bottom pair of dipoles in the bottom row of dipoles,
wherein each of the top coupler and the bottom coupler comprises a first coupling component and a second coupling component, wherein each coupling component is configured to receive a first signal and a second signal, to provide a phase compensation for the first signal and the second signal, and to couple the first signal and the second signal into a first output signal and a second output signal, wherein the first output signal is a mix of the first signal and the second signal at a first power ratio, and the second output signal is a mix of the first signal and the second signal at a second power ratio, wherein the first and second coupling components of the top coupler and the bottom coupler are configured to couple the first signal and the second signal at a first efficiency corresponding to a low

frequency of the frequency band and at a second efficiency corresponding to a high frequency of the frequency band.

2. The antenna array of claim 1, wherein the first efficiency is higher than the second efficiency.

3. The antenna array of claim 2, wherein the first efficiency is -15 dB.

4. The antenna array of claim 1, wherein the first power ratio is an inverse of the second power ratio.

5. The antenna array of claim 4, wherein the first power ratio is 70/30.

6. The antenna array of claim 1, wherein each of the first and the second components of the top coupler and the bottom coupler comprises:

a first signal path coupled to a first input port, the first signal path having a first meander pattern, a first power divider, and a first primary split path and a first secondary split path, the first primary split path coupled to a first coupler segment and the first secondary split path coupled to a second coupler segment;

a second signal path coupled to a second input port, the second signal path having a second meander pattern, a second power divider, and a second primary split path and a second secondary split path, the second primary split path coupled to the second coupler segment and the second secondary split path coupled to the first coupler segment;

a first output port coupled to the first coupler segment; and a second output port coupled to the second coupler segment.

7. The antenna array of claim 6, wherein the first power divider is configured to divide a signal from the first input port between the first primary split trace and the first secondary split trace according to the first power ratio.

8. An antenna array comprising:

a first linear array of antenna dipoles;

a second linear array of antenna dipoles, wherein the antenna dipoles of the first and second linear arrays transmit within a frequency band;

a coupler connecting a first antenna dipole of the first linear array and a first antenna dipole of the second linear array, the coupler comprising a plurality of input ports, each configured to receive a corresponding one of a plurality of input signals, and a plurality of output ports, each configured to output a corresponding one of a plurality of output signals,

wherein the first antenna dipole of the first linear array together with the first antenna dipole of the second linear array are configured to receive the plurality of output signals, and

wherein the coupler is configured to phase compensate the plurality of input signals, divide each of the plurality of input signals, and couple the divided input signal of each of the plurality of input signals with a divided input signal of another one of the plurality of input signals such that each of the plurality of output signals has a desired power ratio.

9. The antenna array of claim 8, wherein each of the antenna dipoles of the first linear array forms an antenna dipole row with a corresponding one of the antenna dipoles of the second linear array.

10. The antenna array of claim 9, wherein the first antenna dipole of the first linear array and the first antenna dipole of the second linear array form a first antenna dipole row at a first end of the first and second linear arrays.

11. The antenna array of claim 10, wherein a second antenna dipole of the first linear array and a second antenna

dipole of the second linear array form a second antenna dipole row at a second end of the first and second linear arrays.

12. The antenna array of claim 11, wherein the first linear array further comprises a third antenna dipole positioned between the first and second antenna dipoles of the first linear array, wherein the second linear array further comprises a third antenna dipole positioned between the first and second antenna dipoles of the second linear array, and wherein the third antenna dipole of the first linear array and the third antenna dipole of the second linear array form a middle antenna dipole row between the first and second antenna dipole rows located at the first and second ends of the first and second linear arrays, respectively.

13. The antenna array of claim 12 further comprising: a second coupler connecting the second antenna dipole of the first linear array and the second antenna dipole of the second linear array, the second coupler comprising a plurality of input ports, each configured to receive a corresponding one of the plurality of input signals, and a plurality of output ports, each configured to output a corresponding one of a second plurality of output signals,

wherein the second antenna dipole of the first linear array together with the second antenna dipole of the second linear array are configured to receive the plurality of second output signals, and

wherein the second coupler is configured to phase compensate the plurality of input signals, divide each of the plurality of input signals, and couple the divided input signal of each of the plurality of input signals with a divided input signal of another one of the plurality of input signals such that each of the plurality of second output signals has a desired power ratio.

14. The antenna array of claim 13, wherein the first coupler and the second coupler are dual couplers, each comprising a first coupling component and a second coupling component,

wherein the first coupling component, of both the first and second couplers, comprises first and second input ports and first and second output ports, and the second coupling component, of both the first and second couplers, comprises third and fourth input ports and third and fourth output ports,

wherein the first antenna dipole of the first linear array receives a first and third output signal associated with the first and third output ports, respectively, of the first coupler, and the first antenna dipole of the second linear array receives a second and fourth output signal associated with the second and fourth output ports, respectively, of the first coupler, and

wherein the second antenna dipole of the first linear array receives a first and third output signal associated with the first and third output ports, respectively, of the second coupler, and the second antenna dipole of the second linear array receives a second and fourth output signal associated with the second and fourth output ports, respectively, of the second coupler.

15. The antenna array of claim 14, wherein, the first and second coupling components are configured such that the first and second output signals of the first coupling component, of both the first and second couplers, have a first power ratio and a second power ratio respectively, and the third and fourth output signals of the second coupling component, of

both the first and second couplers, have the same first power ratio and second power ratio, respectively.

16. The antenna array of claim **15**, wherein the first power ratio is an inverse of the second power ratio.

17. The antenna array of claim **16**, wherein the first power ratio is 70/30.

18. The antenna array of claim **13**, wherein the first and second coupling components, of both the first and second couplers, are configured to couple the divided input signals at a first efficiency corresponding to a low frequency within ¹⁰ the frequency band and at a second efficiency corresponding to a high frequency within the frequency band.

19. The antenna array of claim **18**, wherein the first efficiency is -15 dB.

20. The antenna array of claim **13**, wherein the third ¹⁵ antenna dipole of the first and the second linear array of dipole antennas receive the plurality of input signals without a coupler there between.

21. The antenna array of claim **13**,
wherein a first phase center associated with the first linear ²⁰ array runs through the third antenna dipole of the first linear array and a second phase center associated with the second linear array runs through the third antenna dipole of the second linear array, and
wherein the first and second couplers are configured such ²⁵ that the first and second phase centers are laterally displaced closer to each other between the first and second linear arrays at the first and the second ends of the first and second linear arrays.
